[57] CLAIM

The ornamental design for an ergonomic cushion, as shown and described.

DESCRIPTION

FIG. 1 is a top, side, and end perspective view of an

ergonomic cushion showing my new design, the opposite side being a mirror image of that shown; FIG. 2 is a top, side, and end perspective view thereof, with the head pad portion shown in an alternative position;

FIG. 3 is a top, side, and end elevational view thereof shown partially folded;

FIG. 4 is a top and end perspective view thereof, with the head pad portion shown in an alternative position;

FIG. 5 is a bottom plan view thereof;

FIG. 6 is a top, side, and end perspective view of a second embodiment thereof, the opposite side being a mirror image of that shown;

FIG. 7 is a top, end, and side perspective view of a third embodiment thereof, the opposite side being a mirror image of that shown, and the bottom being plain and unornamented;

FIG. 8 is a top, end, and side perspective view of the embodiment of FIG. 7, with the elbow rest pads shown secured in an alternative position;

FIG. 9 is a top, side, and end perspective view of a fourth embodiment thereof, the opposite side being a mirror image of that shown, and the bottom being plain and unornamented;

FIG. 10 is a top, side, and end elevational view of a fifth embodiment thereof, the opposite side being a mirror image of that shown, and the bottom being plain and unornamented; and

FIG. 11 is a top, side, and end elevational view of the embodiment of FIG. 10, with the elbow rest pads being shown secured in an alternative position.
